MULTIPLEX TELEGRAPHIC AND TELEPHONIC SYSTEM

William Arthur Loth and Joseph Armand Givelet, Paris, France

Application January 17, 1936, Serial No. 59,484
In France January 19, 1935

9 Claims. (Cl. 179—4)

In order to double the number of telephonic or telegraphic messages or communications, on one single circuit, use is made of the persistency of the sound impressions on the ear, the two 5 simultaneous transmissions being alternately broken and "riding" on each other, and the frequency of the interruptions being sufficiently high to allow each auditor on the receiving side to have the impression of continuous reception.

For this purpose, both the transmitter and the receiver sets are provided with valves, placed in opposition and comprising a neutral point, the line being energized or fed by a current of non-audible frequency.

This system, though eloquent in theory, meets with serious difficulties in the practical realization. In fact, the valves with hot filament have a resistance of at least 1000 to 1200 ohms, for it is not possible to realize cathodes of a big size emitting electronic torrents, the heating current expense becoming a prohibitory one. On the other hand, the valves with a gas filling (argon, neon, vapour of mercury or the like) are not able to be used in telephony on account of the audible 20 disturbances caused by the transformation of the molecules of the gas filling, by the setting in of arcs or the like.

It may also be noted that concerning the telephonic connections between two different cities, 30 the public services of the different countries admit only a fading tendency generally below 1,3 napier. Consequently, the hot cathode or gas filling valves are not appropriate, and the object of the present invention is to replace these valves only by rectifiers with a solid contact of low ohmic 35 resistance, such as cuproxide, seleno-iron, zincite-chalcopyrite or similar contacts.

The installation is very much simplified by eliminating the heating current and utilizing only 40 the current for feeding a high frequency local oscillator adapted to interrupt the message at a frequency imperceptible to the ear, so that the message seems continuous. One such oscillator is used for every two stations.

The solid contact rectifiers may have an ohmic 45 resistance for the suitable current direction of only 100 to 200 ohms, and the system is considerably more efficient with respect to that utilizing filament or rarified gas valves. It is then possible to observe the prescribed limits of admitted fading, which was practically impossible with the filament valves.

Another advantage of the solid contact rectifiers, owing to their low resistance, is the possibility 50 of associating these rectifiers with trans-

formers (in the known manner) of a very economical construction. In fact, it is known that the output will be maximum when the impedance of the transformer winding is equal to the inside resistance of the rectifier. This latter resistance 5 being low, the transformer may also have a low impedance, which has still a favourable influence on the fading of the connections.

Finally, the solid contact rectifiers being generally conceived as a pile of washers, intermediary taps may be arranged and the middle point may be displaced to the neutral point of the system in order to obtain the best possible equilibrium, which is very important for eliminating the diaphony and the "riding" or overlapping of the 15 limits of intercutting of the conversations, this being impossible with the lamp valves.

In order to prevent the return of the telephonic currents to the oscillator for dividing or intercutting, it is advantageous, according to the 20 invention, to make use of anti-resonance circuits tuned on an average speech frequency, 800 cycles for example. These circuits offer a great resistance to the passage of the currents of microphonic origin, having an audible frequency 25 and allowing, on the contrary, the higher frequencies to pass easily. Adjustable supplementary resistances may be provided to complete the adjustment of the neutral points.

According to the invention, the anti-resonance 30 circuits may also be replaced by low capacities (of about 1/1000 microfarad) opposing a strong impedance to the audible frequencies and a slight impedance to the higher frequencies. It is also possible to utilize any other filtering system, as 35 known in electrical engineering.

For calling up the receivers invited to enter a 40 conversation, the present invention provides a call finder or annunciating device on each branch with rectifiers placed in the suitable direction and an excitation by direct current or alternating current.

In the case of direct current, this current is supplied to the line with a suitable polarity for 45 releasing the call finders or annunciating elements of the receivers to be called up. This current does not disturb the conversations, and it controls an optical signal when passing in the wanted direction, controlled by the rectifiers.

In the case of alternating current, an inverter 50 has to interfere. The call is effected between a wire and the ground connection on both the lines, the alternating current source having one pole grounded. It is thus possible to call up the wanted station owing to suitable indications for 55

the correct manipulation of the inverter at one and the other station.

The accompanying drawings, given solely by way of example, show two diagrams of connection according to the invention.

Fig. 1 is a diagram of connection of stations provided with call finders, excited by direct current.

Fig. 2 shows a diagram of connection of stations provided with inverters for calling up by alternating current.

As will be seen in Fig. 1, an oscillator 1 supplies the wires 2 and 3 of the line with high frequency currents for obtaining the intercutting of the conversations. Between the oscillator 1 and the wires of the line, anti-resonance devices 4 and 5 are interposed and tuned on about 800 cycles, average frequency of the conversations. Adjustable resistances 6 and 7 ensure the equilibrium of the connections of the oscillator with the wires 2 and 3.

The subscribers are connected to the system by means of plugs, penetrating into jacks 8, 9 at one station and 8', 9' at the other one. These jacks are connected to primary windings 10a of responsive transformers 10 and 11, 10', and 11'. The secondary windings 10b of these transformers are mounted between the wires 2 and 3, and shunted by a capacity respectively 12, 13, 12', 13', which allow the high frequency intercutting circuits to pass through, but prevent the passage of low frequency currents.

Rectifiers 14 and 14', arranged in the same direction, connect the secondary windings to the wire 2. Thus, the jacks 8, 8' may be interconnected, for the current flows in the same direction through 14 and 14'.

Small regulating resistances 15, 15' associated with 16, 16' permit the equilibration of the two branches from a neutral point 17, 17'. On the side extending from 17 or 17' to the wire 3, a call finder or annunciating element 18 or 18' is arranged in combination with rectifiers 19 or 19' respectively of the same direction as 14 or 14'.

As to the other stations 9, 9' which are interconnected, there is the same rectifying arrangement 20 and 20' of the same direction (opposite to that of 14 and 14') with small regulating resistances 21, 21', 22, 22' on both the ends and neutral points 23 and 23'.

The regulating resistances on the ends are provided so as to have the same voltage exactly in the neutral points 17 and 23 on one side, and 17' and 23' on the other side so that it may be possible to join the neutral points with a common neutral point 24 or 24' (which is shown in dotted lines on the drawings) which may be connected to the ground, thus facilitating the grounding of all the frames of elements, transformers for example.

In order to release the annunciating elements, the wires 2 and 3 of the line are supplied with a direct current of the suitable direction for actuating the annunciating elements corresponding to those of the jacks which are to be connected to two subscribers' sets destined to communicate with each other, such as for example 8 and 8'. The annunciating members 18 and 18' are then released simultaneously, the current flows through the two corresponding branches, but it cannot pass to the two other branches and thus, the conversations between 9 and 9' are not disturbed when the jacks are occupied by the subscribers' plugs.

The operator of the central station sees immediately which of the jacks is free and which is the direction of the current to be supplied for exciting the corresponding annunciating members. It is easy to provide the switchboard with clear indications so as to avoid errors.

On Fig. 2, there are arrangements of the same kind, nevertheless the jacks have been arranged at each station on opposite rather than semi-branches, which does not modify at all the working, but permits having one call for each alternating current source 25. The two neutral points 17 and 23 on one hand, and 17' and 23' on the other hand have a common grounding contact 26 and 26'. The alternating current sources 25, 25' of each station have one of their wires connected to the ground; wire 27 and 27' respectively. The other wire comprises an inverter 28, 28' which may be connected to contacts 29, 30, and 29', 30'.

Suppose the key, as shown in Fig. 2, at the first station is in contact with the plug 29, the alternating current will flow in wire 2 and return to the earth 26, exciting the annunciating member 31. At another station, equally, the current will flow through the annunciating member 31' and continue to the earth 26'. The same phenomenon will be produced and the same annunciating members will be released, when at the second station the key is in contact with the plug 29'. In the case of one or the other of the keys being in contact either with the plug 30 or with the plug 30', it is obvious that the other annunciating members 32 and 32' would be excited.

Of course, the subscribers' jacks will be arranged according to the known practice in telephony:

For example, these jacks may be provided with supplementary contacts short-circuiting the corresponding annunciating member during the conversation as soon as the plug is inserted. The elimination of the annunciating member from the circuit increases namely the efficiency of the plant.

Finally, in spite of all precautions taken in order to prevent a disequilibrium, it is still possible that same may somewhat interfere, but in this case, only a slight diaphony would occur during two simultaneous conversations.

However, practice has shown that it is quite possible to suppress the insignificant diaphony which may exist, with the aid of the means which constitute the object of the present invention.

These means are based upon the following considerations:

The currents which produce the diaphony, are always very weak with respect to those of the normal conversations. The voltages corresponding to the diaphonic currents are equally very weak with respect to the voltages which correspond to the normal telephonic currents.

For suppressing the diaphonic currents without affecting the normal currents, use is made of conductors or conductor elements which are not affected by the ohmic principle and whose resistance increases considerably when the voltage furnished to their terminals decreases.

Any conductor corresponding to these conditions may be utilized for suppressing the diaphonic currents. This property of diaphony is especially inherent in the imperfect contacts as well as in most of the detectors used in wireless systems.

More particularly, use will be made of units, such as copper oxides, seleno-irons or the like with at least two elements, placed in opposite di-

rections so as to allow both the alternations to pass continuously without altering the voice.

All of these elements are preferably inserted on each subscriber's line or on the winding of the transformer corresponding to this line.

5 We claim:

1. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; and small resistances arranged in series with said anti-resonance devices.

25 2. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric conditions; anti-resonance capacities tuned on an average speech frequency connected to each branch between said branches and said source; and small resistances arranged in series with said capacities.

3. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said anti-resonance devices; an annunciating member or call finder on each branch and having a winding, and a capacity shunted on the winding of each annunciating member.

4. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resist-

ances for putting the neutral points in the same electric condition; anti-resonance devices tuned on an average speech frequency connected to each branch between said branches and said source; small resistances arranged in series with said anti-resonance devices, a jack and an annunciating member on each branch and constituting a station, said solid contact rectifiers being disposed in opposite directions at each of the stations respectively.

5 5. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said anti-resonance devices; a source of direct current for supplying the call up current, means for sending this current in the suitable direction depending on the annunciating member to be released and the direction of the rectifiers to be crossed.

20 6. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said anti-resonance devices; a ground contact connected to the neutral point on each branch, a receiving station provided at each branch, a source of alternating current at certain of the stations, a reversing change-over switch on each of the stations, connections for sending the alternating current for calling up in the wanted direction, and a ground connection for one of the poles of the alternating current source.

25 7. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said

- anti-resonance devices, a jack and an annunciator mounted in each branch, a blade on each jack, and connections to said blades for switching off the annunciators.
8. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said anti-resonance devices, subscribers' lines leading from said branches, and a unit of two elements of imperfect contact mounted in inverse directions and branched in parallel on each subscriber's line.
9. Multiplex telegraphic and telephonic system for simultaneously carrying two messages on a single circuit, comprising in a circuit a source of current of non-audible frequency for interrupting the normal message-carrying current in said circuit, branches across said circuit, solid contact rectifiers of weak ohmic resistance, placed in opposition in said branches, having a neutral point from which the apparatus on both sides thereof may be balanced potentially, a group of said rectifiers being provided on each side of the neutral point of each branch; variable resistances for putting the neutral points in the same electric condition; anti-resonance devices tuned on an average speech frequency connected to each branch between said branches and said source; small resistances arranged in series with said anti-resonance devices, subscribers' lines leading respectively from the secondary windings of said transformers.

WILLIAM ARTHUR LOTH.

JOSEPH ARMAND GIVELET.
